UNITED STATES PATENT OFFICE.

CHARLES A. BARTLIFF, OF ST. LOUIS, MISSOURI.

DESIGN FOR A PUMP-CURB.

SPECIFICATION forming part of Design No. 28,189, dated January 18, 1898.

Application filed December 20, 1897. Serial No. 662,758. Term of patent 14 years.

To all whom it may concern:

Be it known that I, CHARLES A. BARTLIFF, a subject of the Queen of Great Britain, residing at the city of St. Louis, State of Missouri, 5 have invented a certain new and original Design for a Pump-Curb, of which the following is a full, clear, and exact description, reference being had to the accompanying drawings, forming part of this specification, in which—

10 Figure 1 is a side elevational view of a pump-curb ornamented according to my new design, and Fig. 2 is a top plan view of the same.

This invention relates to a new and original design for pump-curbs; and it consists, generally stated, in a structure having slightly curved side walls, flat end walls, and an ornamented top, the upper plate of which is shaped to form a compound curve, as shown.

15 In the drawings, A indicates the side walls, which, as shown in Fig. 2, are slightly curved or bulged outwardly, the end walls B being

flat, while the corners at the junction of the side and end walls are rounded, as shown.

C indicates the top, which is ornamented by a beading c, forming a belt therearound, said 25 side and end walls conforming substantially to the body portion of the curb.

The top plate D of the cover has a crown portion running off at each end into reverse curves, making substantially a compound 30 curve.

Having thus described my new and original design, what I claim is—

The design for a pump-curb, substantially as herein shown and described. 35

In testimony whereof I hereunto affix my signature, in the presence of two witnesses, this 13th day of December, 1897.

CHARLES A. BARTLIFF.

Witnesses:

F. R. CORNWALL,
HUGH K. WAGNER.
